UNITED STATES PATENT OFFICE.

JESSEY F. HARRELL, OF INDIANAPOLIS, INDIANA.

REFLECTED-LIGHT-DIMINISHING APPARATUS.

1,139,277.

Specification of Letters Patent. Patented May 11, 1915.

Application filed October 10, 1912. Serial No. 724,898.

To all whom it may concern:

Be it known that I, JESSEY F. HARRELL, a citizen of the United States, residing at Indianapolis, in the county of Marion and State of Indiana, have invented new and useful Reflected-Light-Diminishing Apparatus, of which the following is a specification, reference being had to the accompanying drawings and to the letters and figures 10 of reference marked thereon.

This invention relates to means whereby a strong light may be furnished for automobiles, electric or steam locomotives, cars, traction engines, or for other vehicles, when 15 traversing the open country and which light may be diminished or dimmed when entering cities or towns, or when meeting other vehicles traveling in the opposite direction, or when it may be desired to diminish the 20 light, the invention having reference more particularly to a lamp including either electric, gas or other source of light and a focusing reflector, means for movably supporting the source of light relative to the 25 reflector, and means for adjustably moving the source of light.

The primary object of the invention is to provide a powerful light for the above mentioned and other purposes which may be diminished at will, to the end that persons approaching the light shall not be exposed to the blinding influences of a strong light suitable for illuminating the roadway a considerable distance ahead.

35 A specific object of the invention is to provide light diminishing apparatus of such construction as to be adapted to be produced at relatively small cost and be effective and durable, a still further object being to provide means of simple and universally applicable character which may be applied to old as well as new lamp cases and reflectors and to various types of vehicles.

45 With the above mentioned and other objects in view, the invention consists in novel means for supporting and adjustably moving an incandescent lamp or burner or a gas burner relative to a reflector, in order 50 that the intensity of the reflected light may be varied and consequently diminished in intensity as reflected, and the invention consists further in the parts and in the combinations and arrangements of parts hereinafter particularly described and further defined in the accompanying claims.

Referring to the drawings, Figure 1 is a top plan of a portion of an automobile to which the invention is applied as illustrating one of its uses; Fig. 2, a vertical central section of the improved lamp as preferably constructed; Fig. 3, a fragmentary central section of the lamp on an enlarged scale; Fig. 4, a transverse section on the plane of the line A A in Fig. 3; Figs. 5 and 6, perspective views of parts of the invention; Fig. 7, a fragmentary section of the lamp slightly modified to produce gas light; Fig. 8, a sectional diagrammatic view illustrating the continuity and details of the 70 preferred means for operating and controlling the light adjustment apparatus; and Fig. 9, a fragmentary transverse section on the plane of the line B B in Fig. 3.

Similar reference characters in the different figures of the drawings indicate corresponding elements or features of construction herein referred to.

In the drawings the numeral 1 indicates the main frame of an automobile, 2 the engine of the explosion type, 3 the radiator pertaining to the engine cooling system, 4 the steering wheel post or mast, 5 the steering wheel and 6 and 6' the lamp cases, all of which may be variously constructed 80 in detail, the lamp cases illustrated being somewhat similar to those which are adapted to be equipped either for electric lighting or gas lighting, and it is obvious that either one or more lamps may be provided on a 85 vehicle and that the lamp case may be variously modified to suit requirements. Each lamp case has a suitable focusing reflector 7 in its normal forward portion, the reflector being provided on its back with a fixed annular boss 8 which, for the purposes of the invention is arranged on the axis of the reflector and is secured fixedly in the forward end of a tubular or hollow supporting 95 guide 9 which has base extensions 10 and 100 10' on its normal rear end that are fixedly secured to the back 11 of the lamp case, two opposite portions of the wall of the guide having longitudinal slots 12 and 12' therein. The base portion 10 has a fulcrum arm 13 thereon provided with a pivot 14 to which is connected a bell crank having one arm 15 that extends through the slot 12 and when moved may enter the slot 12', the arm having a slot 16 therein, the other arm 17 110 of the bell crank extending at a suitable angle to serve as an operating arm. A

tubular stem 18 is provided which is slidely mounted in the boss 8 so as to be moved through an aperture formed in the focusing portion of the reflector, and it has a guide collar 19 on its rear end that is slidely guided in the guide 9 and has also slots 20 and 20' in opposite portions of the wall thereof, and a wrist-pin 21 is secured in the wall and extends through the slot 16 of the arm 15 which extends through the slots in the guide head. The normal forward end of the stem 18 has a suitable plug 22 therein to which either an incandescent electric burner 23 or a gas burner 24 is suitably connected in a well known manner. The reflector may be provided with a protecting glass or lens 25. The plug 22 when adapted for holding an electric burner has suitable filling 26 therein in which circuit wires 27 and 28 are held and properly terminated so as to afford a circuit with the electric burner commonly known as an incandescent lamp. The wires extend rearward through the stem and past one side of the base portion and out through the casing to be connected with any desired source of electricity.

In case gas light is desired or required a flexible gas tube 29 in lieu of the wires is brought into the rear end of the guide 9 and into the stem 18 to the holding plug 22 in which it may be suitably connected with the gas burner 24. Each lamp case may be variously supported, as by means of a stand 30, various vehicles necessitating various means for supporting the lamp case or cases thereon.

Various connecting means may be employed for enabling a person to manually operate the lighting apparatus and control the illumination at a distance from him, and in the operation of automobile lamps it is preferable to provide a steel wire rod 31 for one lamp and a branch wire rod 31' secured to the rod 31 for another lamp, the rods being relatively thin and flexible and provided with suitable couplers 32, 32' connected each to the arm 17 of a lamp mechanism. In order to guide the rods throughout their length to prevent them from springing laterally when pushed they are inserted in suitable guide tubes or cases 33 and 33' respectively which may be bent in arranging them with respect to the vehicle structure, and they extend into the lamp cases nearly to the bell crank arms and are suitably supported by means of anchors 34. The connected portions of the rods 31 and 31' are incased in a Y comprising a stem 35 and two branches 36 and 37 connected respectively to the guides 33 and 33', a hollow guide 38 being connected to the stem 35 and incasing and guiding the portion of the rod 31 that extends to the operator's position, the end of the rod having a suitable coupler

39 thereon which preferably is connected to an operating lever 40 suitably mounted on a latch bar 41 which in the present case is secured to the steering wheel post 4 in proximity to the steering wheel 5. The incasing 70 guides of the operating rods are provided with a suitable number of bracing holders 42 secured to the post 4 and elsewhere as may be desired.

In practical use the lamp burner at which 75 the light is produced is held in the position relatively close to the focusing portion of the reflector so that the light beams are projected a considerable distance ahead and a brilliant reflected light results, and when it 80 is desired to avoid blinding or partially blinding persons facing the light, the stem 18 is moved forward a suitable distance and carries the source of light away from the focusing portion of the reflector toward or 85 to the glass 25 with the result that the light is de-focused and only dimly reflected, and therefore is not of such intensity as to be objectionable, but is sufficient to light the road either in streets or when moving at 90 slow speed on roads in the open country.

Having thus described the invention, what is claimed as new is:—

1. Reflected light diminishing means including a supported case, a focusing reflector supported in the case, a lamp device, a holding stem movably guided in the case for supporting the lamp device at different positions within the reflector, actuating means movably supported within the case 100 adapted for gradually changing the position of the holding stem, controlling means operatively connected with the actuating means and extending to a point remote therefrom, and means for latching the controlling means to hold the stem and the lamp device in graduated position.

2. Reflected light diminishing apparatus including a supported focusing reflector provided on its axis with a guide, a stem 110 movably supported by the guide and provided with a longitudinally movable flexible controlling device extending therefrom, means for guiding the controlling device and controlling the flexibility thereof, and a lamp device connected with the stem.

3. Reflected light diminishing apparatus including a supported focusing reflector provided with a guide, a stem movably supported by the guide, a flexible controlling rod, coupling means connecting the rod with the stem, means for guiding the rod and controlling the flexibility thereof, and a lamp device connected with the stem.

4. Reflected light diminishing apparatus including a supported focusing reflector provided with a guide, a stem movably supported by the guide, a flexible controlling rod, coupling means connecting the rod with the stem, a supported tubular casing envel-

oping and guiding the rod, and a lamp element carried by the stem opposite to the reflector.

5. Reflected light diminishing apparatus including a supported focusing reflector provided with a guide, a stem movably supported by the guide and having a relatively long and flexible controlling device operatively connected therewith, a lamp element carried by the stem opposite to the reflector, and means for tortuously guiding the controlling device and controlling the flexibility thereof.

6. Reflected light diminishing apparatus including a supported focusing reflector provided with a hollow guide, a stem movably mounted in the guide, a lamp element carried by the stem opposite the reflector, an arm pivotally supported and connected with 20 the stem and having an operating arm thereon, a rod connected to the operating arm, means for guiding the rod, and a conductor extending into the hollow guide and through the stem to the lamp element.

25 7. Reflected light diminishing apparatus including a case, a focusing reflector fixedly supported in the case and provided on its focusing portion with a hollow guide, a stem movably mounted in the guide, a lamp element mounted on the stem within the reflector, an arm pivoted in the case and connected with the stem, a rod extending through the case and operatively connected with the arm, and a conductor extending 30 into the case and the hollow guide and also through the stem to the lamp element.

8. The combination of a plurality of lamp cases, a plurality of guides supported in the plurality of cases respectively, a plurality 40 of focusing reflectors fixedly supported in the cases adjacent to the guides respectively, a plurality of lamp elements movably supported by the guides respectively to move toward or from the focusing portions of the reflectors, a plurality of operating devices supported respectively by the cases and operatively connected with the plurality of lamp elements for control thereof, a hollow guide having a plurality of guide branches respectively extending to the cases, and an operating rod movable in the guide and having branches movably extending 45 through the guide branches and connected respectively with the operating devices.

55 9. The combination with a motor vehicle, a steering wheel mounted on the vehicle, a lamp case mounted on the vehicle distant from the steering wheel, a focusing reflector

mounted in the lamp case, and a lamp element in the case, of guiding means movably supporting the lamp element opposite the focusing portion of the reflector to permit movement of the lamp element toward or from the focusing portion, a conductor for supplying the lamp element with a current for producing light, and movable operating connections connected with the guiding and supporting means and extending approximately to the steering wheel.

10. The combination with a motor vehicle 70 having controlling means, and an operator's station in proximity to the controlling means, of a case mounted on the vehicle having a guide fixed therein, a stem movably supported by the guide, a lamp element connected to the stem, a focusing reflector mounted in the case opposite the lamp element, a conductor extending through the stem to the lamp element, and movable operating connections connected 75 with the stem and extending through the case to the operator's station.

11. The combination with a casing having a focusing reflector therein, of a hollow guide secured to the case and also to the 85 reflector, a bell-crank pivoted in the case, a stem movably mounted in the guide and connected with the bell-crank, a lamp element movably supported by the stem opposite the focusing portion of the reflector, 90 a conductor extending through the stem to the lamp element, and an operating rod connected to the bell-crank and extending through the case.

12. The combination with a motor vehicle 95 having controlling means, and an operator's station in proximity to the controlling means, of a focusing reflector mounted on the vehicle, a transparent element supported at the front of the reflector, a connecting 100 device extending substantially from the operator's station to the reflector, lamp means for producing light adjacent to the focusing portion of the reflector or adjacent to the inner side of the transparent 105 element and controlled by the connecting device, operating means supported in proximity to the operator's station for controlling the connecting device, and means for latching the operating means.

In testimony whereof, I affix my signature in presence of two witnesses.
